UNITED STATES PATENT OFFICE.

RICHARD T. FRYE, OF BLAUVELT, NEW YORK.

TOILET-FIXTURE SUPPORT.

Application filed April 10, 1928. Serial No. 263,916.

My invention relates to toilet fixture supports and particularly to improvements in the construction disclosed in my prior application for water closet supports, Serial No. 5 165,923, allowed December 19, 1927.

An object of the invention is to provide a mounting for toilet fixtures such as sinks, wash-stands, water closets, urinals, etc., which is of simple construction, may be 10 quickly and readily installed, and which is a general refinement of my allowed application above identified.

Further the invention provides a toilet fixture mounting embodying a support for the 15 flush valve sleeve which is carried by and supported directly from the wall plate, also embodying a support 18 for flush water supply sleeve.

With the preceding and other objects and 20 advantages in mind, the invention consists in the novel combination of elements, constructions and arrangement of parts to be hereinafter specifically referred to, claimed and illustrated in the accompanying drawings, wherein:

Figure 1 is a view partly in side elevation and partly in section of my improved toilet fixture mounting in operative position to support the fixture, and showing connection 30 for lead waste pipe;

Figure 2 is a horizontal sectional view taken on line 2—2 of Figure 1;

Figure 3 is a rear elevation of the wall plate and associated flush valve sleeve support;

Figure 4 is a vertical sectional view of the device and connection for iron pipe; and

Figure 5 is a front elevation of the wall plate.

Referring to the invention in detail a wall plate 5, cruciform in configuration and having a central opening 6, is provided, and is adapted to be supported in a vertical plane against or in a wall by a vertically adjustable 40 threaded rod 6 rising from a base pedestal 7 and engaging a recess 8' in the lower end of the lower leg of the wall plate. A pipe coupling 8 is received in the central opening and projects beyond both faces thereof and has its 45 inner end threadedly or solderedly engaged with a conventional waste pipe 9. The forward end of the coupling is reduced to afford an annular shoulder 10 flush with the outer interface of the wall plate, and receives an internally threaded clamping nut 11 which is of 50 a greater diameter than the coupling and

engages the wall plate to hold it in position relative to the coupling.

To connect the wall plate with a toilet fixture 12, a plurality of bolts 13 pass through the wall plate and base of the toilet fixture and support the latter in a position where a circular recess 12, surrounding the outlet opening in the fixture, receives the forward end of the coupling. The bolts 13 are provided with heads 14 whose inner faces are rounded, as at 15, and are adapted for universal adjustment in rounded recesses 16 in the inner faces of the legs of the wall plate. The legs of the wall plate are also provided 70 with transverse slots 17 communicating with the rounded recesses and receive the shanks of the bolts.

A circular opening 18 is provided in the uppermost leg of the wall plate for the reception of a horizontally disposed sleeve 19, passing transversely through a building wall, as illustrated in Figure 1, and through which the flush water supply pipe 20 of a conventional flush valve 21 for the toilet fixture 80 passes. A set screw 22 passing transversely through this leg of the wall plate projects into the circular opening 18 and engages the sleeve 19 to retain the latter against longitudinal displacement.

In order to centralize the wall plate on the coupling member and to sustain it against tilting movement thereon before the clamping nut is threaded home, the wall plate is provided with horizontally aligned slots 23 at 90 diametrically opposite points of the central opening 6 and receive laterally projecting lugs 24 carried by the coupling at diametrically opposite points.

To support a horizontally disposed flush valve handle receiving tube 25 which passes transversely through the wall above the wall plate, an angularly disposed rod 26 is threadedly engaged with the wall plate, as at 27, and carries a collar 28 at its upper end which receives the projecting end of the tube, the collar carrying a set screw 29 for engagement with the tube. In order to detachably connect the collar with the rod an interiorly threaded socket 30 is formed on the collar 100 and is threadedly engaged with the upper end of the head.

It will be observed that with my invention the toilet fixture may be expeditiously installed and that the wall plate will be effectively supported in position. Also the flush valve handle receiving tube will be effectively 110

supported in place by the collar 28 carried by the angularly disposed rod.

What is claimed is:—

1. In a toilet fixture mounting, a vertically disposed wall plate having a central opening, a pipe coupling passing transversely therethrough for connection with a toilet fixture and waste pipe respectively, a nut threadedly engaged with the outer end of the coupling 10 and engaging the wall plate to clamp the same in position, fastenings for connecting the wall plate and the base of a toilet fixture, and lugs projecting from the coupling and engaged with the wall plate to hold the latter 15 against rotation relative to the coupling.
2. In combination a vertically disposed wall plate having a central opening, a pipe coupling passing through the opening and having a shoulder flush with one face of the 20 wall plate, a clamping nut threaded on one end of the coupling and abutting the shoulder and wall plate to retain the latter in a vertical plane, and fastening elements associated with the wall plate and projecting laterally there- 25 through to be connected with the base of a toilet fixture.
3. In combination a vertically disposed wall plate having a central opening, a pipe

coupling passing through the opening and having a shoulder flush with one face of the 30 wall plate, a clamping nut threaded on one end of the coupling and abutting the shoulder and wall plate to retain the latter in a vertical plane, fastening elements associated 35 with the wall plate and projecting laterally therethrough to be connected with the base of a toilet fixture, a rod detachably connected with the wall plate, and a collar detachably mounted on the rod and adapted to receive and support the projecting end of a tube lo- 40 cated above the wall plate.

4. In a toilet fixture mounting, a wall plate to be positioned against or in a building wall, a coupling passing transversely therethrough for connection with a waste pipe and toilet 45 fixture respectively, fastenings for connecting the wall plate and base of the toilet fixture, a rod extending vertically from the wall plate, and a collar carried thereby for the reception of a flush valve handle receiving 50 tube disposed above the wall plate.

Signed at Blauvelt in the county of Rock-
land and State of New York this 7th day of
April, A. D. 1928.

RICHARD T. FRYE.
